Primary Examiner — Sandra Snapp*Assistant Examiner* — Ieisha N Price(74) *Attorney, Agent, or Firm* — Nixon & Vanderhye P.C.(57) **CLAIM**

The ornamental design for a fastening device, as shown and described.

DESCRIPTION

FIG. 1 is a perspective view of the fastening device;
 FIG. 2 is a second perspective view thereof;
 FIG. 3 is a rear view thereof;
 FIG. 4 is a front view thereof;
 FIG. 5 is a right side view thereof, the opposite side being a mirror image;
 FIG. 6 is a bottom view thereof; and,
 FIG. 7 is a top view thereof.

1 Claim, 4 Drawing Sheets(56)
